UNITED STATES PATENT OFFICE.

WILLIAM J. SCHENKEL, JR., OF BROOKVILLE, INDIANA.

INCUBATOR.

Application filed October 3, 1921. Serial No. 505,033.

To all whom it may concern:

Be it known that I, WILLIAM J. SCHENKEL, Jr., a citizen of the United States, residing at Brookville, in the county of Franklin and State of Indiana, have invented certain new and useful Improvements in Incubators, of which the following is a specification.

This invention relates to incubators and the primary object of the invention is to provide an improved incubator embodying a novel heating means, which is so constructed that the incubator will be evenly heated, without the entrance of any fumes or obnoxious vapors from the heating means. The air supplied to the incubator is taken exteriorly of the heating means but heated by said means, thereby insuring the entrance of fresh warm air into the incubator, which is so necessary to the proper incubation of the eggs.

Another object of the invention is to provide a novel hot water heating device for the incubator and a novel means of disposing and arranging the hot water heat radiator pipe in the incubator, so that the maximum amount of efficiency will be obtained therefrom, said hot water heating device also providing means for heating the air taken into the incubator, so as to insure not only the heating of the interior of the incubator but also the fresh air supplied thereto.

Another object of the invention is to provide a novel means for constructing the body portion of the incubator, whereby the best results can be obtained therefrom, and whereby the heat radiating pipe can be readily exposed to view, and readily connected to or disconnected from the heating plant or device.

A further object of the invention is to provide an improved incubator of the above character, which will be durable and efficient in use, one that will be simple and easy to construct, and one which can be placed upon the market at a minimum cost.

With these and other objects in view, the invention consists in the novel construction, arrangement and formation of parts, as will be hereinafter more specifically described, claimed and illustrated in the accompanying drawings, forming a part of this specification, in which drawings:—

Figure 1 is a perspective view of the improved incubator.

Figure 2 is an enlarged fragmentary verti-

cal section through a portion of the incubator, taken on the line 2—2 of Figure 4, illustrating the novel heating plant carried thereby.

Figure 3 is a detail transverse sectional view through the heating plant, taken on the line 3—3 of Figure 2.

Figure 4 is a fragmentary section through the incubator taken on the line 4—4 of Figure 2, illustrating the novel heating plant and expansion tank thereof, of the incubator.

Figure 5 is a fragmentary horizontal section through the incubator showing the means of arranging the hot water heat radiator pipe therein, and the warm air distributing pipe.

Figure 6 is a transverse vertical section through the improved incubator.

Figure 7 is a fragmentary vertical section through the incubator showing the novel means of associating the heating lamp with the incubator.

Referring to the drawings in detail, wherein similar reference characters designate corresponding parts throughout the several views, the letter A indicates the incubator proper B, the novel heating plant therefor; and C, the novel means of controlling the flow of hot air through the heating means and the warm air from the incubator.

The incubator A may be of any desired size for incubating the desired number of eggs and may contain one or more trays 10 for receiving the eggs. As shown in the drawings, the incubator is of a size for receiving two of the trays 10, but in forming an incubator for a single tray, substantially the same form of incubator and heating means would be carried out. The incubator A includes the main body portion 15, which may be supported by corner legs 16 of the desired form and construction. The body portion of the incubator A includes the front wall 17, the rear wall 18, the end walls 19, the bottom wall 20, and the top wall 21. These walls 18, 19, 20, and 21 are preferably formed with two spaced skins 22 and 23 of the desired material, and the spaces intermediate the skins are filled with some suitable non-heat conducting material 24. The top wall 21 is preferably formed as a single unit, so that it can be readily removed to expose the interior of the body portion 15 of the incubator A, for a purpose which will herein-

after more fully appear, and this top wall 21 is held in place by suitable fastening elements 25, which extend entirely through the same into the front wall 17, end wall 19 and 5 rear wall 18. The body portion 15 may be divided transversely by a central partition 26, forming a pair of compartments for the trays 10 which can be supported upon suitable cleats or guides 27. These trays 10 consist of an upper rectangular frame 28 and a 10 lower rectangular frame 29, between which is adapted to be positioned and held the wire screen 30 upon which the eggs are adapted to rest. The lower frame 29 carries suitable supporting cleats 31 for preventing the sagging of the wire screen 30. The frames 28 and 29 can be constructed in any preferred manner in order that a rigid and cheap construction will be had. The 15 front wall 17 consists of spaced lower and upper longitudinally extending cleats 34 and 35, and inner spaced upper cleats 37. The cleats 35 and 37 are joined by a longitudinally extending stop strip 38 and the 20 space between the cleats 37 and 35 may be filled, if so desired, with some suitable non-heat conducting material similar to the material 24. The outer lower cleat 34 supports the outer longitudinally extending 25 door 40, while the lower wall 20 inwardly of the cleat 34, hingedly supports a pair of doors 41, which are adapted to close the two compartments defined by the central partition 26 and these doors 41 are provided with glass panels 42. The outer longitudinally extending door 40, is provided in front of the doors 41 with transparent panels 43, and these panels are normally closed by hinged swinging plates 44. As shown, these 30 plates 44 are hinged upon pins 45, and are held against swinging movement at their lower ends by resilient clips 46. It can be seen that when it is desired to look into the compartment and see the eggs on the trays 45 10, it is merely necessary to swing the plates 44 on their pins 45 and glance through the panels 43 and 42. When it is desired to remove the trays, the front door 40 is swung down on its hinges 47 and then the inner 50 doors 41 are swung downward on their hinges. The doors 40 and 41 may be held closed by suitable pivoted latches 48 if so desired. One end wall 19 of the body 15 of the incubator A is adapted to support the 55 heating plant B and this wall is suitably treated to receive the frame, as will be more fully described. It can be seen, however, that this wall 19 is provided with an inwardly extending opening 50 and the outer 60 skin of this wall 19 is recessed as at 51 for receiving a portion of the heating plant and for forming a seat therefor, as will be hereinafter more fully apparent.

The heating plant B comprises the inner 65 flue 52 which is surrounded by a cylindrical

hot water chamber 53. This chamber 53 is provided with an inwardly extending integral lateral enlargement 54, which constitutes the main portion of the hot water heating plant or boiler. The laterally 70 extending compartment 54 has provided extending longitudinally therethrough a relatively large hot air heating flue 55, which extends at right angles to the main vertically disposed heating flue 52 and extending through the laterally extending hot air heating flue 55 is a plurality of hot water heating tubes 56, which communicate with the upper and lower portions of the laterally 75 extending hot water compartment 54, and it 80 can be seen that the hot vapors arising through the flue 52 will flow through the laterally extending hot air flue 55 and around the hot water tubes 56. The hot water chamber and laterally extending compartments 53 and 54 are surrounded by an outer wall 57, which has opening into the same the laterally extending hot air flue 55 and the hot vapors are adapted to flow into the space designated by the numeral 58 between 85 the outer wall 57 and the walls defining the hot water compartment 53 and the laterally extending chamber 54. The rear end of the wall 57 surrounding the hot water chamber 53 and the compartment 54 is provided with laterally extending extensions 59 defining an 90 opening 60 through which the hot vapors are adapted to flow into the atmosphere after circulating around the hot water compartment 53 and chamber 54. It can be seen that by referring to Figure 3 of the drawings, top and bottom walls 61 and 62 are provided, which close the upper ends of the space 58 defining the hot air circulating 95 space and the hot water chamber and compartment. A second wall 63 is disposed around the heating chamber in spaced relation to the wall 57 defining a warm air space 64, which communicates with an inwardly 100 extending warm air pipe 65 which is disposed through the opening 50. The wall 63 and the whole heating plant is enclosed by a suitable casing 66 of non-heat conducting material, and this casing 66 has the top and 105 bottom walls 67 and 68 thereof provided with openings 69 to permit the entrance of fresh air into the warm air space 64 and air into the flue 52 and to permit the chimney 70 of the heating lamp 71 to extend into the main flue 52. The chimney 70 may be of the 110 desired shape or configuration and is adapted to be detachably fitted on the heating lamp 71. The heating lamp 71 may be of any desired character, and as shown includes the fount 72 for receiving the oil or other burning fluid and this fount is provided with a suitable burner. The fount 72 can be detachably fitted upon a supporting base 73, which is carried by a bracket 74. This bracket 74 is of angular construction and has 115 120 125 130

its inner upper end threaded as at 75 and fitted in a threaded socket 76 carried by the lower wall 20 of the body 15 of the incubator A. Outwardly extending flanges 77 are carried by the casing 68 or portions of the walls forming the hot air chamber or warm air chamber, and these flanges are secured by suitable detachable fastening elements 78 to the mentioned end wall 19 of the incubator. It can be seen that by removing the fastening elements, the whole heating plant can be easily removed from the incubator. The lower end of the laterally extending hot water chamber 54 has communicating therewith the return hot water pipe 78, while the upper end of this chamber has communicating therewith the hot water feed pipe 79. These pipes 78 and 79 are connected in any preferred manner to the hot water heat radiating pipes 80 which will now be described.

The hot water heat radiating pipes 80 are arranged in the nature of a coil, and as shown these pipes 78 and 79 extend through the inner end of the warm air distributing pipe 65, which will be hereinafter more fully described. The hot water feeding pipe 79 communicates with the outer convolutions 81 of the hot water heat radiating pipes 80, and this outer convolution 81 is of relatively large diameter and extends around the incubator close to the end, front and rear walls thereof, and then communicates with the intermediate convolution 82, which is of slightly smaller diameter than the outer convolution 81. The intermediate convolution 82 then communicates with the inner convolution 83, which is of relatively smaller diameter than the intermediate convolution 82. The end of this inner convolution communicates with the return pipe 78, which leads into the bottom portion of the hot water compartment 54. These pipes constituting the hot water heat radiating means may be carried by suitable depending loops or straps 84, which are secured to the top wall 21 and by removing the top wall 21, these pipes will be carried therewith. If so desired, a slip joint connection between the return and hot water feeding pipes 78 and 79 and the heat radiating pipe 80 can be had and when it is desired to remove the top wall 21 and the radiator 80, the heating means B proper can be first removed so as to disconnect the hot water feeding the return pipes 78 and 79 from the heat radiating pipe 80.

The warm air distributing pipe 65 extends longitudinally into the incubator and terminates short of the end wall 19 which is opposite to the mentioned end wall 19 which carries the heating plant B. This pipe is provided with suitable outlets 85 for the warm air. It can be seen that this warm air will enter around the chimney 70 and flow through the space 64 around the hot air space 58 from whence it receives its rise in

temperature and then upwardly into the warm air distributing pipe 65. If desirable, the pipe 65 can also be carried by the top wall 21 and have a slip joint connection with a suitable nipple or the like carried by the wall 63 defining the warm air space 64.

A water expansion tank 90 is provided for the hot water heating plant and this expansion tank may be detachably secured to the mentioned wall 19, in any preferred manner. The lower end of the expansion tank has communicating therewith a pipe 91 which communicates with the lower end of the hot water return pipe 78.

A novel damper 95 is provided for the heating plant B, and this damper is of a substantially inverted conical form and is adapted to seat upon the wall of the upper opening 69 formed in the casing 66 and on the upper edge of the central flue 52, which is extended as at 96 to provide a seat for the damper. It can be seen that when the damper 95 is in its lowered position it closes the passage of the warm air from the casing, as well as the exit of the hot air from the lamp through the flue 52. When the damper 95 is raised, the hot air from the lamp will flow directly through the flue 52 and out of the casing and will not circulate around the hot water tubes 56 and through the chamber 58 surrounding the hot water chamber 53 and compartment 54. When the damper is in its lowered position, the warm air from the warm air distributing pipe 65 will be prevented from flowing directly out of the body portion 15 of the incubator A. When this damper is raised, however, the hot air will be permitted to flow directly out. This damper can be controlled by any suitable form of thermostat, (not shown). The thermostat may be located at any desired point within the body portion 15 of the incubator A, and as shown the same is positioned approximately at the center thereof and is connected with the damper by means of a suitable operating rod 98. This operating rod 98 has its outer end angled as at 99, and extended into the damper 95 and connected for swinging movement with a cross brace rod 100 arranged in the damper.

Now, when the incubator is in operation, it will be seen that the hot vapors from the lamp will rise through the chimney 70 into the main flue 52 and then into the horizontal flue 55 around the hot water tube 56 and into the chamber 58 around the hot water chamber 53 and compartment 54 out through the outlet 60. This circulation of the hot air around the hot water tank will of course, heat the water therein which will flow through the hot water feed pipe 79, through the heat radiating pipe 80 and back to the return pipe 78 to the lower end of the hot water tank. As the hot water tank be-

comes heated, air will be sucked into the casing 66 through the lower opening 69 in the casing 66, and this air will circulate around the hot air chamber or space 58 and 5 then flow into the hot air distributing pipe 65 as heretobefore described, into the body portion 15 of the incubator.

From this construction, it can be seen that the incubator is not only effectively 10 heated in an efficient and cleanly manner, but that a sufficient quantity of warm fresh air is supplied thereto.

If desirable, the end walls 19 may be provided with openings 101 and these openings 15 can be covered by suitable light protecting hoods 102 carried by the outer surface of the end walls 19.

When the incubator becomes heated to the desired temperature, the damper 95 will be 20 operated by the thermostat in the usual manner and be lifted from off of its seat, permitting the escape of the hot vapors directly from the flue 52 and escape of the warm air from the incubator.

25 It is apparent, of course that the distance the damper 95 is lifted from off of its seat, regulates the amount of hot and heated air which is permitted to escape from the flue 52 and from the body portion of the incubator.

If desirable, the inner ends of the hot water heat radiating pipes 80 may be connected to an outlet pipe 110, which can extend exteriorly of the body portion 15 of the 30 incubator.

35 This pipe may be provided with a suitable pet cock 111. This pipe will permit the escape of air if the same becomes trapped in the system, and may be used for the draining of water from the system if 40 desirable.

From the foregoing description, it can be seen that an improved incubator has been provided, of exceptionally simple and durable construction, which embodies a 45 novel hot water heating means for heating the incubator and a novel means for supplying fresh warm air to the interior of the incubator.

Changes in details may be made without 50 departing from the spirit or scope of this invention; but,

I claim:

1. In an incubator, the combination with a body to be heated, of a combined heating 55 and ventilating means including a radiator within the casing, a boiler disposed exteriorly of the casing and connected to the radiator, said boiler having a central flue extending therethrough, a jacket extending 60 around the flue communicating with the central flue and having atmospherical connection at the rear end thereof, a second jacket surrounding the first jacket having a lower open end to permit the entrance of fresh air 65 into the same, a heating medium communi-

cating with the central flue, a warm air distributing pipe communicating with the space intermediate the first and second mentioned jackets, and a single damper for controlling the exit of the heated vapors from the central flue and the warm air from the space intermediate the first and second mentioned jackets. 70

2. In an incubator, the combination with a body including an egg chamber to be 75 heated, of combined heating and ventilating means including a radiator disposed within the egg chamber, a boiler disposed exteriorly of the body communicating with the radiator having a central flue there- 80 through, a laterally extending chamber forming a portion of and communicating with the boiler, a laterally extending flue disposed through the laterally extending portion of the boiler and communicating 85 with the central flue adjacent to the central portion thereof, a hot air jacket surrounding the boiler and communicating with the laterally extending flue and with the atmosphere at a point diametrically opposite 90 said laterally extending flue, a warm air chamber surrounding the hot air chamber having a lower open end to permit the entrance of fresh air into the same, and a centrally disposed inwardly extending warm 95 air distributing pipe communicating with the upper end of the warm air chamber positioned in the egg compartment intermediate the heat radiator.

3. In an incubator, the combination with 100 a body including an egg chamber to be heated, of a heating means therefor including a plurality of radiator pipes arranged within the egg chamber, a boiler disposed exteriorly of the body having a central flue 105 therethrough, a laterally extending extension formed on the boiler having a laterally extending flue therethrough communicating with the central portion of the centrally extending flue, a plurality of water tubes extending through the laterally extending flue and communicating with the upper and lower portions of the laterally extending extensions of the boiler, hot water distributing 110 and return pipes connected with the laterally extending portion of the boiler and the radiator pipes, a heating element extending into the central flue, a hot air chamber surrounding the boiler and communicating with the laterally extending flue and having 115 atmospherical connection at the rear end thereof whereby heated vapor from said heating element is adapted to circulate through said flues around the water tubes and the boiler, and means for controlling 120 the flow of heated vapors from the upper end of the central flue.

4. In an incubator, the combination with a body having an egg chamber therein to be 125 heated, of a combined heating and ventilat- 130

ing means including radiator pipes disposed within the egg compartment and a boiler disposed exteriorly of the body having a central flue therethrough, a laterally extending flue 5 extending through the boiler and communicating with the central flue, a hot air chamber surrounding the boiler communicating with the laterally extending flue at one end and with the atmosphere at the opposite end, 10 a warm air chamber surrounding the hot air chamber having communication at its lower end with the atmosphere to permit the entrance of fresh air into the same, a warm air distributing pipe extending into the egg 15 compartment and communicating with the upper end of the warm air chamber, a heat insulated casing extended around the warm air chamber having aligned openings formed in the upper and lower ends thereof communicating with the warm air chamber, a heating element extending into the flue, and a single damper adapted to seat upon the central flue and the wall of the opening in the upper end of the casing, and means for 20 operating said damper.

5. In an incubator, the combination with a body including an egg compartment, of a heating means for the body including a casing, a hot water heating plant disposed in 25 the casing, hot water heat radiating pipes disposed in the body communicating with said plant, the plant being disposed in spaced relation to the inner surface of the casing forming a warm air chamber between the casing and the hot water heating plant, a warm air distributing pipe disposed in the egg compartment intermediate the hot water heat radiating pipe communicating with said warm air chamber, the 30 casing having upper and lower openings formed therein defining inlet and outlet openings for the air, a central flue formed

in the heating plant in alignment with said upper and lower openings, heating means for communication with the flue, and a single 45 conical damper arranged to engage the wall of the upper opening and the upper end of the central flue for controlling the exit of warm air from the casing and the heated vapors from said central flue.

6. In an incubator, the combination with a body having an egg compartment therein to be heated, of a hot water heating plant therefor including a radiator having a plurality of communicating concentrically arranged pipes disposed in the compartment, the pipes gradually decreasing in diameter toward the central portion of the compartment, a boiler having a central flue therethrough disposed exteriorly of the casing, 50 a laterally extending compartment communicating with and forming a part of the boiler, water distributing and return pipes communicating with the radiator and with the laterally extending chamber, the laterally extending chamber having a horizontally disposed flue therein communicating with the centrally disposed flue, the hot air chamber surrounding the boiler and communicating with the laterally extending 55 flue, hot water tubes extending through the laterally extending flue and communicating with the upper and lower portions of the laterally extending compartment of the boiler, the hot air chamber having an outlet therein at the outer portion thereof, a casing arranged in spaced relation and surrounding said boiler and said hot air chamber, a heating element disposed in operative relation to the centrally disposed flue, a 60 valve seat formed on the upper end of the flue, and a damper adapted to normally sit upon said seat.

WILLIAM J. SCHENKEL, Jr.
